90,717

DESIGN FOR AN AUTOMOBILE BUMPER GUARD

Frank C. Howard, Chicago, Ill.

Application June 28, 1933. Serial No. 48,576

Term of patent 3½ years

To all whom it may concern:

Be it known that I, FRANK C. HOWARD, a citizen of the United States, residing at Chicago, in the county of Cook and State of Illinois, have invented a new, original, and ornamental Design for an Automobile Bumper Guard, of which the following is a specification, reference being had to the accompanying drawing, in which—

Fig. 1 is a front elevation, and

Fig. 2 is a side view of the article showing my new design.

I claim:

The ornamental design for an automobile bumper guard as shown.

In testimony of which I affix my signature.

FRANK C. HOWARD.
